UNITED STATES PATENT OFFICE.

WILLIAM H. FITZGERALD, OF HARTFORD, CONNECTICUT.

DESIGN FOR A THERAPEUTIC PADDLE.

Application filed March 10, 1923. Serial No. 5,434. Term of patent 3½ years.

To all whom it may concern:

Be it known that I, WILLIAM H. FITZGERALD, a citizen of the United States, residing at Hartford, in the county of Hartford and State of Connecticut, have invented a new, original, and ornamental Design for Therapeutic Paddle, of which the following is a specification, reference being had to the accompanying drawing, forming part thereof. Figures 1 and 2 are opposite side views of a therapeutic paddle embodying the invention.

What I claim is:

The ornamental design for a therapeutic paddle, as shown.

WILLIAM H. FITZGERALD.

In presence of—

ELIN C. GARDELL,
HEATH SUTHERLAND.
